UNITED STATES PATENT OFFICE.

JESSE P. WILSON, OF DUNCAN, OKLAHOMA, ASSIGNOR OF ONE-HALF TO MARY C. EVANS.

ATTACHMENT FOR SEWING-MACHINES.

1,172,417.

Specification of Letters Patent. Patented Feb. 22, 1916.

Application filed March 22, 1915. Serial No. 16,118.

To all whom it may concern:

Be it known that I, JESSE P. WILSON, a citizen of the United States, residing at Duncan, in the county of Stephens and State of Oklahoma, have invented certain new and useful Improvements in Attachments for Sewing-Machines, of which the following is a specification, reference being had to the accompanying drawings.

10 This invention relates to certain improvements in attachments for sewing machines, and it is an object of the invention to provide a novel and improved attachment of this general character adapted to be applied 15 to the needle bar of a sewing machine to facilitate the operation of embroidering material upon the work table of the machine.

It is also an object of my invention to provide a device of this general character having novel and improved means whereby the same may be conveniently applied and removed, which is efficient in use, which will operate without obscuring the design or pattern, and in which the parts are combined and arranged in such a manner as to secure maximum simplicity of construction.

Furthermore, it is an object of my invention to provide in connection with an attachment of this general character, novel 30 and improved means whereby requisite padding may be properly delivered relative to the needle when so required.

The invention consists in the details of construction and in the combination and arrangement of the several parts of my improved attachment whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view in perspective of an embroidery attachment constructed in accordance with an embodiment of my invention, the coacting parts of a sewing machine being indicated by dotted lines; and Fig. 2 is a view in perspective of the member

adapted to be employed in connection with my improved embroidery attachment, a co- 55 acting spool being indicated by dotted lines.

As disclosed in the accompanying drawings, A denotes the needle bar of a sewing machine, the needle B being held therein in a conventional manner through the medium 60 of the set screw C.

My improved embroidery attachment, as herein disclosed, is preferably produced from a single strand of wire of requisite gage and having one extremity 1 flexed to afford a 65 hook member adapted to be detachably engaged with the needle bar A. The portion of the wire immediately adjacent the extremity 1 is vertically disposed, as at 2, for a predetermined length with the lower extremity of said portion 2 terminating in the inwardly disposed substantially loop member 3 terminating in the coil 4 positioned slightly in advance of the vertical portion 2, said strand being continued horizontally, as 70 at 5, a predetermined distance and at right angles to the vertical portion 2 and having produced therein in substantial alinement with the portion 2 the upstanding loop or eye 6. The portion 5 terminates in the perpendicularly directed horizontal portion 7 having produced intermediate its length an upstanding loop or eye member 8 and is continued in a third horizontal portion 9 parallel to the horizontal portion 5, hereinbefore referred to, and terminates in a coil 10 in alinement with the coil 4, hereinbefore referred to, and said wire is then directed over to and twisted about the loop 3, hereinbefore referred to, and being twisted 90 to afford the horizontal coil 11 rearwardly of and immediately adjacent the loop 3 and through which the needle B is adapted to be directed. The wire is then extended horizontally in a plane substantially parallel to 95 the vertical portion 2 and terminates in the upstanding hook member 12 adapted to be detachably engaged with the set screw C.

100 whereby it will be perceived that my improved attachment may be maintained in applied position in an effective and convenient manner.

As is believed to be self-evident, the horizontal portions 5, 7 and 9 afford a frame adapted to engage the material to be operated upon and possess sufficient resiliency to

permit the requisite adjustments of the material, and it will also be particularly observed that the construction of my improved device is such as to in no way obscure the design upon the material.

It often occurs in embroidering that padding is required. For this purpose, my invention contemplates employing in connection with the attachment, hereinbefore referred to, a pad member assuring the proper delivery of the padding which is generally in the nature of a thread. As herein disclosed, the pad member is also produced preferably of a single strand of wire of requisite gage and, as herein disclosed, said strand comprises a horizontal portion 14 terminating at one extremity in the vertical coils 15 affording an eye, for a purpose which is believed to be self-evident. The opposite extremity of the portion 14 is directed downwardly and vertically, as at 16, and has its intermediate portion formed to afford a latch member 17 adapted to engage the set screw D of the presser foot E. The lower extremity of the vertical portion 16 is bent to afford the horizontally disposed foot member 18 comprising the loops 19 and from said foot the wire is continued upwardly, as at 20, and coiled about the portion 14 as indicated at 21, said portion 21 intermediate its length being extended upwardly to afford the standard 22 on which is adapted to be mounted a spool S having wound thereon the pad thread.

In applying the pad member in position, the member has its portion 16 disposed within the loop 8 of the embroidery attachment, while the portion 20 is positioned within the loop 6 of the embroidery attachment whereby the foot 18 is properly positioned relative to the needle B.

The thread from the spool S is directed through the coil or eye 15 and downward and through the coil 4 of the embroidery attachment and in the loops 19 of the pad member, whereby it will be perceived that said padding thread is at all times positioned substantially directly beneath the needle B.

From the foregoing description, it is thought to be obvious that an attachment constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein

shown in carrying out my invention in practice.

I claim:

1. As a new article of manufacture, an embroidery attachment for a sewing machine including a member comprising a foot, vertically disposed members, one of said members being provided with means engageable with a presser foot, and a horizontally disposed member connected to the upper extremities of the vertical members, said horizontal member being provided with an extension to afford a mounting for a spool.

2. An attachment of the character described comprising a yieldable work engaging member provided with engaging means, said work engaging member being provided with loops, and a pad member comprising a foot, vertically disposed members adapted to be received within the loops of the work engaging member, and a spool supporting means carried by the member.

3. In combination with an embroidery attachment for a sewing machine, a pad member capable of detachable engagement with the embroidery attachment and comprising a horizontal member, a foot member connected with the horizontal member and in spaced relation thereto, said foot member being provided with loops, and spool supporting means carried by the horizontal member.

4. In combination with an embroidery attachment for a sewing machine, a pad member capable of detachable engagement with the embroidery attachment and comprising a horizontal member, a foot member connected with the horizontal member and in spaced relation thereto, said foot member being provided with loops, and spool supporting means carried by the horizontal member; one extremity of the horizontal member being provided with an eye.

5. In combination with an embroidery attachment for a sewing machine, a pad member capable of detachable engagement with the embroidery attachment and comprising a horizontal member, a foot member connected with the horizontal member and in spaced relation thereto, said foot being provided with loops, spool supporting means carried by the horizontal member, and engaging means carried by the pad member at a point intermediate the horizontal member and the foot.

In testimony whereof I hereunto affix my signature in the presence of two witnesses.
